Patented Dec. 16, 1975

238,043

ADJUSTABLE OIL FILTER WRENCH

Donald J. Shanklin, Granada Hills, Calif., assignor to
Orion Industries, Inc., Torrance, Calif.

Filed Nov. 18, 1974, Ser. No. 524,637

Term of patent 14 years

Int. Cl. D8—05

U.S. Cl. D8—22

FIG. 1 is a perspective view of an adjustable oil filter wrench showing my new design;

FIG. 2 is a top view of an adjustable oil filter wrench shown in FIG. 1;

FIG. 3 is a back view of an adjustable oil filter wrench shown in FIG. 1;

FIG. 4 is a left-hand end view of an adjustable oil filter wrench shown in FIG. 1; and

FIG. 5 is a right-hand end view of an adjustable oil filter wrench shown in FIG. 1.

I claim:

The ornamental design for an adjustable oil filter wrench, substantially as shown and described.
